UNITED STATES PATENT OFFICE

2,620,078

BALL TRANSFER MEANS

Otto Sloan, Melvindale, and Andrew M. Klarich,
Dearborn, Mich., assignors to Hayes Sloan
Products Company, a corporation of Michigan

Application July 29, 1949, Serial No. 107,488

4 Claims. (Cl. 214—130)

1

The invention pertains to a ball transfer mechanism and more particularly to means for carrying a ball between the ends of ball guides as the ball passes through a processing machine, such for example as that disclosed in the joint application of George W. Hayes and Otto Sloan, Serial No. 9,865 filed February 20, 1948, for Ball Cleaning and Polishing Apparatus.

It is an object of the invention to provide a ball transfer mechanism which is simple, rugged, durable and reliable in operation.

It is also an object of the invention to provide a ball transfer mechanism which transfers balls without injury to the surface of the ball.

It is a further object of the invention to provide a ball transfer arrangement comprising a pair of ball guides in sloping positions so that a ball is moved along either one by gravity, said guides being positioned one above the other with the lower end of the upper guide being above the higher end of the lower guide and the improved ball transfer being cooperatively disposed for transferring balls from the sloping upper ball guide to the sloping lower ball guide.

Further objects and advantages are with the scope of the invention, such as relate to the arrangement, operation and function of the related elements of the structure, to various details of construction and to combinations of parts, elements per se, and to economies of manufacture and other features as will be apparent from a consideration of the specification in conjunction with the drawings disclosing specific embodiments of the invention, in which:

Fig. 1 is an elevational view of the ball transfer mechanism, as viewed from the side which is disposed toward the rear end of the machine, shown in lowermost position with the uppermost position shown in dotted lines;

Fig. 2 is an elevational view showing the end of the ball transfer mechanism adapted to be mounted to the frame of the machine;

Fig. 3 is a perspective view showing the improved ball transfer, installed in such a machine, as viewed from the rear end of the machine; and

Fig. 4 is a plan view of a cam.

Referring more specifically to the drawings, it will be seen that a ball receiver 10 is provided comprising a head plate 11 of substantially a triangular conformation having a pair of ball receiving members 13 extending therefrom in a spaced apart relation suitable for receiving a ball 15 rolling down thereunto from an upper sloping ball guide 17. The sloping ball guide 17 may be

2

a trough-like structure, as represented, or it may be a pair of suitably spaced guide rails, as shown in the application previously mentioned.

The spaced ball receiving members 13 have reduced pins 19 extending through the head plate 11 and secured as by lock nuts 21. These ball receiving members 13 are smooth and symmetrical pin-like elements and may be tapered or covered with soft material, for receiving the balls with a minimum of friction to avoid any friction marks on the outer surface of any ball transported by the mechanism. Such a ball 15 rolls down the upper sloping ball guide 17 and passes to a position upon the ball receiver 10 which is held up to receive the ball by a pair of spaced arms 25 and 27. The lower arm 27 is secured pivotally to the lower portion of the head plate 11 by a screw 29 extending therethrough. The upper arm 25 is apertured at this end to be pivotally disposed upon an intermediate reduced portion of the adjacent ball receiving member 13 near the head plate 11. These two support arms 25 and 27 extend from the ball receiver 10, in a spaced apart substantially parallel relation, for pivotal attachment at the other ends on a web 31 of an angular mounting bracket 33 on a pivotal support pin 35 and a shaft 34 extending therethrough. The other web 39 of the mounting bracket 33 is apertured suitably for reception of screws 41, by which attachment is made on the frame 56 of the machine.

For holding the ball receiver at its uppermost position at the proper time when a ball will pass down the upper ball guide, a pair of cam arms, 35 or actuator arms, 43 are provided extending across the two support arms and secured pivotally on opposite sides thereof by screws 45. The bolts 45 are loose to provide a pivotal connection and to avoid creating a tight clamping relation between the actuator arms and the parallel support arms. Spacers 47 are provided on these screws 45 to hold the cam arm 43 spaced apart so that a screw 49 may be passed through the upper ends of these arms for rotatively supporting a cam roller 51 which rolls upon a cam 53'. This cam is suitably shaped for holding the ball receiver either at the upper position adjacent the lower end of the upper ball guide 17 for receiving a ball therefrom, or adjacent the upper end of a lower ball guide 55, disposed thereunder, for depositing a transferred ball thereupon. This lower ball guide 55 slopes in the opposite direction so that the deposited ball rolls down the lower guide away from the ball transfer. The two sloping ball guides 17 and 55 correspond to

the two pairs of sloping ball guide rails disclosed as part of the machine in said co-pending application, wherein the main cam shaft 53 carries and drives this cam 53'. This assures that the ball receiver is carried to the respective upper and lower positions in proper timed relation to the other operations of the machine 56 so that the ball is properly received and transferred down to the lower sloping ball carrying guide. Fig. 4 shows a cam 53' of a suitable shape for controlling the operation of the ball transfer mechanism, in such a machine. A guard rail 57 is preferably provided on a cross-piece 59 of the machine supporting a soft rubber buffer 60, such as a piece of hose, in a suitable position to stop the ball as it rolls upon the ball support members 13 from the upper ball guide 17, as shown in Fig. 3. Greater rigidity may be imparted to the ball transfer by providing a brace 61 having one end secured to the lower arm 27, by screws 63, and the other end being apertured to fit upon the shaft 34 at a position spaced thereon as rigidly maintained by a tubular spacer sleeve 65 thereon.

It will be seen that the ball receiver is so positioned and the receiving members 13 extend from the head plate 11 of the ball receiver in a parallel relation and suitably spaced to pass on the opposite outer sides of the ball guides so that the ball passes readily to these members from the upper ball guide 17, and the ball is then deposited upon the upper end of the lower ball guide to roll away by gravity. It is the slope of the ball guides 17 and 55 which causes the balls to move along by gravity and, in handling large heavy balls such as bowling balls, a slight slope is adequate for this purpose.

When carried by the carrier members 13, the weight of the ball 15 is off center relative to the arms 25 and 27. So it is desirable to provide for adequate rigidity, as by extending the pivot shaft 34 off to one side from the arms and holding this extended end of the shaft in a bearing plate 67, which is firmly secured to any structural member 69, of the machine. This arrangement, together with the brace 61, provides the ball transfer with suitable rigidity, even though the ball 15 is off-center relative to the arms 25 and 27.

It is apparent that within the scope of the invention modifications and different arrangements may be made other than herein disclosed, and the present disclosure is illustrative merely, the invention comprehending variations thereof.

What is claimed as the invention is:

1. A ball transfer device comprising, a mounting bracket, a ball receiving head plate, a pair of pin-like ball receiving members extending perpendicularly from said head plate in a parallel and suitably spaced apart relation for receiving a ball to rest thereon while being transferred, jointed parallelogram means having one end pivotally mounted on said bracket with the other end extending therefrom, means pivotally supporting said ball receiving head plate on the extended end of said parallelogram to be carried in the plane of movement of said parallelogram means for receiving a ball between said spaced members at one position and movable to carry the ball to a different position.

2. Ball transfer mechanism comprising, an angle iron mounting bracket having one web suitably apertured for bolting to a stationary support in a vertically disposed position, a ball receiving head plate, a pair of pin-like ball receiving members projecting perpendicularly from said head plate in suitably parallel and spaced apart relation for receiving and holding a ball, an upper arm, means pivotally securing one end of said upper arm to the upper portion of the other web of said bracket, means pivotally joining the other end of said upper arm to an upper portion of said head plate, a lower arm, means pivotally securing the ends of said lower arm to the lower portion of said head plate and to the lower portion of said other bracket flange in a parallel relation to said upper arm so that said head plate may be swung about said mounting bracket in a plane coinciding with the plane of movement of said arms while maintaining a predetermined level position, and actuator means connected for swinging said arms to carry said ball receiving head plate to various different positions.

3. In a ball transporting and transfer arrangement the combination of, upper elongated ball guide means sloping slightly for transporting a ball by gravity, lower elongated ball guide means disposed under said upper ball guide means and sloping slightly in the opposite direction for transporting a ball in the opposite direction, a ball receiver having a pair of extending pin-like members spaced apart suitably to be disposed on opposite sides of the ends of said ball guides, and movable support means for supporting said ball receiver to move it adjacent the lower end of said upper ball guide with said pair of spaced pin-like members on opposite sides thereof to receive a ball therefrom and movable to an alternative position adjacent the upper end of said lower ball guide with said spaced pin-like members on opposite sides thereof to deposit the received ball thereon so that a ball may be transferred from the upper ball guide to the lower ball guide.

4. A ball transporting and transfer arrangement in accordance with claim 3 and further characterized by said movable support means being a pair of parallelogram arms disposed to swing in a plane substantially perpendicular to said ball guides to support the ball receiver substantially level as it moves between the two ball guides.
